UNITED STATES PATENT OFFICE

PRATHER DOLEN, OF BEATRICE, NEBRASKA

DISHWASHING MACHINE

Application filed February 20, 1930. Serial No. 429,969.

This invention relates to a dish washing machine and has for its object, broadly, to provide a machine particularly adapted for household use which will be complete for washing, rinsing and drying dishes, said machine to be of such construction that it will be convenient and durable, and to consist of few and simple parts so that it may be manufactured at a limited cost.

10 One of the specific objects of the invention is to provide means for concentrating and directing water with greater force than ordinary for washing the dishes.

Another object is to provide a combined 15 dish rack and tray of arcuate form including foraminous pockets or receptacles for use in connection with a water trough of specific construction and a particular arrangement of movable dasher-blades for throwing 20 water.

The invention includes a specific form for the trough at the bottom of the tub so that all of the water will be forcibly moved by 25 action of the dasher-blades and that only a limited quantity of water will be required for operation. The invention also includes a specific form for a combined rack and tray found to be of great advantage for use in connection with the nested dashers of the shafts and 30 the trough of the tub.

With the foregoing objects in view and others to be mentioned the invention presents a new and useful construction, combination and arrangement of parts as described herein and claimed, and as shown in the accompanying drawings, it being understood that the drawings illustrate only one embodiment of the invention and that changes in form, size, proportions and minor details may be 40 made without departing from the spirit of the invention or sacrificing any of its advantages, said changes being within the scope of the invention as claimed.

45 In the drawings, Fig. 1 is a view in side elevation, partly broken away, of the dish washing machine. Fig. 2 is a view of a spraying attachment used for rinsing the dishes. Fig. 3 is an end view, partly broken away, of the machine. Fig. 4 is a view showing a pair of operating shafts in transverse section and

showing pairs of opposed dasher-blades for said shafts.

Fig. 5 is a plan view of the machine, the lid and rack being removed to clearly show the arrangement of the pair of operating shafts 55 and their dasher-blades. Fig. 6 is an end view of a combined dish-rack and tray used in some instances, and Fig. 7 is a side view of the same.

Fig. 8 is a detail illustrating the tub in 60 transverse section to closely show its trough and the operating parts of the machine. Fig. 9 is a side view of one of the dish-holders for the combined rack and tray generally used for dish-washing and shown in Figs. 3 and 8, 65 and Fig. 10 is an end view of the same. Fig. 11 is a detail showing a pair of transversely inclined dasher-blades for an operating shaft, the latter being in section. Fig. 12 is a plan or side view showing a part of an operating shaft 70 and a pair of transversely inclined dasher-blades mounted thereon.

Referring now to the drawings for a more particular description, the invention is shown and described in connection with a frame 13 75 of any suitable construction. However, it is preferably of rectangular form in plan and elevation, and strips of angle-iron are preferred for the frame.

Numeral 14 indicates a tub which is rectangular in plan. The sides and ends of the tub are suitably secured to the upper parts of the frame, and the open top of the tub is provided with a lid 15.

By referring to Figs. 3 and 8 of the drawings it will be noted that the curved bottom *a* of the tub is provided, midway between its sides, with a depression or trough, said trough providing a pair of opposed concave surfaces *b*, that part of the bottom of the trough between the uniformly concave surfaces *b*, being flat as indicated at *c*. This trough and its opposed concave surfaces are used for certain purposes to be hereinafter described.

I provide a combined dish-holder and tray 95 consisting of a pair of inverted V-shaped bars or frame-members 16 connected at their ends by means of cross-strips 17, handles 18 being provided for said strips or bars 16 for use in removing the tray from its supports 19 or 100

for placing it in operative position on said supports.

Numerals 20 indicate elongated foraminous baskets or dish-holders best shown in Figs. 9 and 10 of the drawings, each provided at its top with a pair of rods 21 adapted to be mounted in loops 22 of the metallic strands used in the construction of said baskets, said rods 21 being adapted to be disposed in notches α which open upon the top of the bars 16.

The construction selected for the dish-holders or baskets 20 is not a matter of importance, except that it is necessary to permit water to move freely therethrough so that the dishes therein may become washed and rinsed when water is thrown, dashed or splashed from the trough by means to be described. Also it is necessary that the baskets and dishes therein shall be completely exposed when the water is thrown upwardly from the trough, and therefore the baskets 20 are disposed in spaced relation, and each basket extends downwardly toward the trough from the V-shaped frame 16.

In operation, it will be understood that the combined dish-holder and tray may be placed in its operative position shown in Figs. 1, 3 and 8 of the drawings and may, by use of the handles 18, be readily removed, and whenever desired, the baskets 20 may be removed from the arcuate frame.

Numerals 23 indicate a pair of parallel shafts which are journaled at their ends in bearings 24 supported by the frame, and by means of suitable pack nuts 25 any leakage from the trough will be prevented during the rotatable movements of the shafts.

It will be noted that the operating-shafts are disposed parallel, side by side in the trough and that each concave surface b of the trough is concentric with the shaft adjacent thereto.

Each shaft 23 is provided with a plurality of dasher-blades 26. By referring to the drawings it will be seen that each shaft at one of its sides is provided with aligning-blades 26 disposed in spaced relation and that recesses 27 are formed between said blades, the opposite side of each shaft also being provided with similar dasher-blades 26 disposed in alignment and with similar recesses 27 therebetween, the blades at the respective sides of the shafts being disposed approximately 180 degrees from each other.

As best shown in Fig. 5, each shaft 23 is provided with a gear wheel 28 and since these wheels are in engagement the shafts will rotate in reverse directions. One of the shafts is provided with a pulley 29, and by means of a band 30 which engages the pulley 29 and the pulley of the shaft of the electric motor 31, the shafts 23 may be rotated.

While I have shown and described specific means for rotating the shafts 23, and prefer

the exact construction as described, I do not wish to be understood as limiting myself with exactness to these features nor to any feature or detail except those found to be new and of great convenience in operation.

It will be appreciated that the use of the trough in which the dasher-blades are nested is of great advantage since the blades move closely adjacent to the concave surfaces b , and since the blades of each shaft, during operation, move through the recesses between the blades of the other shaft, the working parts are concentrated within a limited space, and therefore only a limited quantity of water will be required for each dish-washing or cleansing operation.

Numeral 32 indicates a waste pipe provided with a valve 33, and any suitable arrangement may be made for discharging water from the trough. In operation a sufficient quantity of hot water is placed in the trough to cause the blades 26 to be partly submerged, and the rotation of the shafts will cause the water to be violently thrown against the baskets and dishes therein to cause almost immediate washing.

Numeral 34 indicates an intake pipe for water fed through a horizontal supply pipe 34a for conducting water to the trough under control of a valve 35, and numeral 36 indicates a supply pipe for fluid under pressure used for spraying or cleansing the dishes, this pipe being under control of a valve 37, and for this last named purpose the spraying device 38 is used and may be connected with the pipe 36, the lid 15 being removed to permit the use of said spraying device.

Numeral 39 (Figs. 6, 7) includes a modified form for a dish-holder. It consists in part, of a pair of arcuate strips 40, said strips being connected at their upper and lower edges and ends with rods 41, and the lower rods 41 being connected by means of strands 42. It will be understood that the dish-holder 39, as described, operates also as a tray and by use of its handles 43 may be placed in operative position and supported upon the lugs or brackets 19 as a substitute for the combined dish-holder and tray already described.

Numerals 44 (Fig. 4) illustrates longitudinally curved dasher-blades for the pair of operating-shafts, and these blades may be used if desired, the arrangement of said blades being in spaced relation at the opposite sides of the shafts the same as heretofore described. Also, as best shown in Figs. 11 and 12 of the drawings, dasher-blades 45 may be used if desired. These blades are inclined transversely. They are disposed in spaced relation at opposed sides of the shafts 23, and since the transverse inclination of the blades at one side of a shaft is reverse to the inclination of the blades at the opposite side thereof, the water will be thrown angularly against the baskets and dishes to great advantage.

In operation, water will be thrown upwardly and at nearly all angles from the trough against the basket, and dishes therein, and water which moves through the baskets 5 will be deflected from the lid 15 and will again be thrown against the dishes. Numeral 46 indicates a separate basket for containing cutlery.

While two operating shafts have been 10 shown and described and are preferred, a single operating shaft provided with dasher-blades would be operative, and it is considered within the scope of the invention, the new and useful feature being that a trough 15 is used having a concave surface concentric with the shaft so that the blades, during operation will move equi-distant from said concave surface, so that a lesser quantity of water will be required than by any other construction. 20

I claim as my invention,—

In a dish washing machine, a tub having the lower portions of its side walls gradually curved downwardly and inwardly toward one 25 another, then extending downwardly substantially parallel to one another, and a flat bottom joining said side walls together, to provide a narrow liquid receiving trough, an inverted V-shaped bar supported within the 30 tub and by said side walls above the trough, a plurality of foraminous dish holding baskets suspended from said bar, and means in said trough for directing liquid therein up the curved side walls and through the baskets. 35

In testimony whereof, I affix my signature.
PRATHER DOLEN.
